US00D868105S

(12) **United States Design Patent** (10) Patent No.: **US D868,105 S**
(45) Date of Patent: **** Nov. 26, 2019**

(54) **DISPLAY SCREEN OR PORTION THEREOF WITH GRAPHICAL USER INTERFACE**

(71) Applicant: **Apple Inc.**, Cupertino, CA (US)

(72) Inventors: **William Martin Bachman**, San Jose, CA (US); **Colin Bennett**, San Francisco, CA (US); **Monika E. Gromek**, Oakland, CA (US); **Richard D. Lyons**, San Francisco, CA (US); **Eliza J. Von Hagen**, Sunnyvale, CA (US); **Aled Williams**, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/655,857**

(22) Filed: **Jul. 9, 2018**

Related U.S. Application Data

(63) Continuation of application No. 29/606,435, filed on Jun. 5, 2017, now Pat. No. Des. 822,711.

(57) **CLAIM**

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
